Specification for Design.

Patented June 7, 1921.

Application filed October 5, 1918. Serial No. 257,072. Term of patent 7 years.

To all whom it may concern:

Be it known that I, THEODORE C. WHEATON, Jr., a citizen of the United States, and a resident of Washington, District of Columbia, have invented a new, original, and ornamental Design for a Bottle, of which the following is a specification, reference being had to the accompanying drawing, forming a part hereof, in which—

Figure 1 is a plan view, and

Fig. 2 is a side view of the bottle.

The surface ornamentation illustrated extends entirely around the bottle.

I claim:

The ornamental design for a bottle, substantially as shown.
